UNITED STATES PATENT OFFICE.

HIRAM T. HALL, OF OAKLAND, CALIFORNIA.

FIRE-FIGHTING SYSTEM.

1,109,833.

Specification of Letters Patent.

Patented Sept. 8, 1914.

Application filed March 22, 1913. Serial No. 756,174.

To all whom it may concern:

Be it known that I, HIRAM T. HALL, a citizen of the United States, residing at Oakland, in the county of Alameda and 5 State of California, have invented certain new and useful Improvements in Fire-Fighting Systems, of which the following is a specification.

This invention relates to improvements 10 in a system for fire fighting for installation on street corners or similar locations, the objects of the invention being to produce such a system as can be put into operation and instantly used by any person without 15 the necessity for ringing in an alarm to a central station and waiting for the fire apparatus to arrive. Also a system which can be used as a single unit by electrically coupling up a number of separate hydrant units 20 and having them all coöperate to throw their water from any one desired hydrant, or in which each separate hydrant can be used by itself without interfering in any way with the operation of the others. Also a system 25 which is simple and efficient in operation, and which needs no expensive force of men for its upkeep or operation, and which will need very little care or attention either when in operation or not in use.

30 These objects I accomplish by means of the particular adaptation and arrangements of the water mains, electrical circuits, and other parts thereof, as will more fully appear by a perusal of the following specification and which is shown in the drawings, in which:

Figure 1 is a diagrammatic view of a complete unit of four hydrants as installed on the four corners of a city block. Fig. 2 is 40 an enlarged sectional side elevation showing the installation and power plant on any one of these corners. Fig. 3 is a sectional elevation of a solenoid-operated water gate-valve.

45 On the drawings, similar numerals refer to the same parts on the several views.

In the diagrammatic view shown in Fig. 1, the water piping is represented by heavy lines, and the electrical circuits by light 50 lines.

Referring now more particularly to the same, A, B, C, and D represent four separate corner units, each one having a motor E, F, G, and H, operating centrifugal pumps 55 I, J, K, and L, respectively, the said pumps

operating between water main connections 1, 2, 3, and 4, and hose connections 5, 6, 7, and 8 respectively. Between each pump and the water main is a solenoid-operated water gate-valve 9, 10, 11, and 12, such as 60 is shown in Fig. 3, while between the pumps and their respective hydrants are short water connections 13, having similar solenoid operated valves 14, 15, 16, and 17 therein, the said water connections 13 being commonly connected to an auxiliary water main 18 running around the entire block, and being common to all the units A, B, C and D. Between the said water connections and the hydrants are solenoid-operated water gate- 70 valves 19, 20, 21, and 22 respectively. Each of the motors E, F, G, and H has a switch 23 operated by a relay 24, connecting the said motors with a main source of power 25, made common to all the said motors by the 75 wires 26.

In a controller box 27 located with the hose container 28 on each corner are a plurality of switches 29, hand operated, there being one of these switches for each hydrant 80 which the system controls. This set of switches is common to all the separate units, and each operates the mechanism of itself or any of the others as hereinafter set forth, and all are identical in construction and operation, hence one only will be described herein.

The power necessary for the operation of the various solenoid valves may be the same as that for the motors, or may be a separate 90 source such as 30 as shown, this latter method necessitating less wiring than the former, and therefore preferable on account of its simplicity.

The circuits closed in the operation of this 95 system is as follows: Suppose the scene of the fire which is to be extinguished is in the vicinity of unit A. The person who has discovered the said fire opens the controller box 27, and closes the switch 31, the same 100 being preferably labeled to identify it with the unit which it controls. (At the same time the hose 32 in the container 28 should be pulled out ready for use, the hose being normally connected with the water mains.) 105 Now it will be seen that when the switch 31 is closed, two contacts are made. In one, it will be seen that the circuit passes from the battery 30 through the switch 31, through the relay 33, through the solenoid-valve 9 110

and through the relay 24. This, it will be seen, opens the valve 9 by a mechanism hereinafter described, allowing the water to pass from the mains to the pump I, and also 5 closes the switch 23, thus causing the motor E to turn. With the other contact, it will be seen that the current passes from the battery, through the switch 31, through the wire 34, thus operating the solenoid valve 10 19, thus permitting the flow of water to the hydrant. It will be seen that the relay 33 is not now caused to operate, as the armature 35 of the same is not in circuit, being 15 on an open circuit. Thus it will be seen that the throwing of switch 31 starts the unit A to working.

Should it be found that the fire is too big for the stream of water which can be pumped by the one motor E, switch 36 is 20 closed, bringing into operation unit B, by the following means: On closing this switch, two contacts are made, the current passing from the battery 30 through the conductor 37, through the relay 38, through the solenoid valve 10, opening the same, through the relay 24 of the motor F, starting the same. The current also passes through the second contact made by the switch 36, through the conductor 39 to the armature of 25 the relay 38, thus actuating the same, and causing the solenoid valve 15 to operate, thus opening the water connection 13 and permitting the water pumped by the pump J to flow through the auxiliary main 18. 30 Now it will also be seen that conductor 39 is also connected with the armature 35 of relay 33 of the first unit. This causes the said armature to contact with the relay, thus permitting the current to pass therethrough 35 to operate the solenoid valve 14 and open the water connection or by-pass 13 of unit A, thus allowing the water which is being now pumped by unit B to pass therethrough, and out at the hydrant along with the water being 40 pumped by the motor of unit A.

The operation and action of switches 40 and 41 operating and controlling units C and D respectively, is substantially the same as that described for the switch 36 and unit 45 B, each one opening such valves and makes such switch connections as will permit the water to be pumped by these units C and D and passed through the auxiliary main 18 and out through the hydrant of unit A. 50 The same operation may be done at each of the separate units A, B, C, and D with the same results, each of the sets of switches at these units operating identically, and produces the same results with the remaining 55 units.

If desired, any preferable and simple method may be employed for interlocking the switches 31, 36, 40, and 41 one with the other, so that no one switch can be closed 60 without closing the preceding one in the ro-

tation in which they are arranged to work, thus doing away with any possibility of burning out any of the motors or otherwise deranging any part of the system.

Of course it will be obvious that more 70 units may be controlled from one unit if so desired, but for ordinary uses one set of these units composed of four street-corner hydrants and the apparatus connected therewith will be all that can be well and practically controlled. 75

Referring now more particularly to the type of apparatus as preferably used in connection with my improved system, as shown in Fig. 2, all the working parts of any of 80 the units are placed beneath the sidewalk in a cement-lined chamber 42, access being had thereto for the purposes of inspection etc., through a manhole 43 in the said sidewalk, the only part of the apparatus showing 85 above the ground being the hose container 28 and the controller box 27, thus protecting the same from weather etc., and making it practically "fool-proof."

Referring now to the type of solenoid valve used for operating the gates in the water mains, Fig. 3 shows any one of the several valves, all being the same in construction and operation. In the same, 44 represents the solenoid, attached to a piston-valve 45 adapted to slide in a valve-box 45^a, having inlet water-port 46 therein, outlet port 47 leading therefrom, and ports 48 and 49 leading from the valve-chamber into a cylinder 50, in which runs a piston 51, this piston being suitably connected with a gate 52 in the valve 53 in the pipe line. The operation of the same is as follows: Normally the piston-valve 45 is seated so that the water inlet 46—which is connected with the city water mains or other water pressure source—is in open communication with port 48, thus keeping the said water pressure against the piston 51, and so keeping the gate 52 closed. When the current flows through the solenoid 105 44 and actuates the same, the piston-valve 45 is pulled in, and the water then flows through port 49 to the other side of the piston 51, thus causing the said gate 52 to open, at the same time the water which was in the 110 cylinder 50 passing out back through port 48 and through the outlet port 47, being forced therethrough by the pressure of the water against the opposite head of the piston 51. Thus it will be seen that I have invented such a system as will substantially 115 fulfil the claims made thereon.

While not shown, if desired an alarm system, to operate when any one of the switches at any unit is thrown in, may be installed, to 120 alarm in any desired location in the city, building, or elsewhere, to notify a fire-fighting force, or those in charge of a building, etc., that one of the units in the system has been turned, the number of the unit being 130

designated on the alarm, similar to those used on elevators or in hotels for call-service.

The cellar or chamber 42 in which the apparatus is located is preferably sloped down at one corner, and a connection of some kind made at that point with the sewers, so as to drain off any water which may seep in through the concrete or walls, or which may leak in through the man-hole 10 during a rain storm.

While I have shown and described my improved system as being used only for street protection, it is also adapted to be installed in buildings of various kinds, such as hotels, 15 office-buildings and department stores, where the operating mechanism may be located, or may be adapted for installation on large ships, thus insuring instantaneous fire protection to any part of the ship.

20 While I have described and shown herein the present and preferred embodiment of my invention, still in practice such deviations from such detail may be made as do not depart from the spirit of the invention.

25 Having thus described my invention, what I claim as new and useful and desire to secure by Letters Patent is:

1. A fire-fighting system, comprising a plurality of suitably spaced pumping units, 30 means for operating any one of the same independently or in combination with the remainder thereof, and suitable means located at each of said units whereby and from which the operating means of any or all of 35 the said units may be actuated, as set forth.

2. A fire-fighting system, comprising a plurality of power operated and electrically controlled water pumping units connected with a suitable water supply, and means at 40 each and every unit for actuating the said

electric controlling means at the said unit and at all other units if desired.

3. A fire fighting system comprising a plurality of suitably disposed power-operated pumping units connected independently 45 with a suitable water supply, an endless auxiliary water main connecting all the said units, water gate-valves suitably located on and between the said water supply, pumps, and auxiliary main, electrical operating 50 means on said valves, and hand-operated means for actuating said operating means, said hand-operating means being located at each of the said units and capable of controlling from any of the same the operation 55 of the electrical operating means on any or all of the said units, as and for the purpose set forth.

4. In a fire fighting system in combination, an endless auxiliary water main, a plurality of pumping units arranged along said main and adapted to pump into the same, motors for operating said units, valves intermediate said units and said auxiliary main, and hand controlled electrical means whereby the operator at any one unit may start said unit and thereafter any or all of the other units, said means being adapted to open the valve between the first unit started and the auxiliary main as well as the valve 70 between any additional unit and the auxiliary main upon the starting of such additional unit.

In testimony whereof I affix my signature in presence of two witnesses.
